METHOD OF RECONSTITUTING LUMBER AND PRODUCT THEREOF

Roy C. Horne, 20 Dean Way, Chico, Calif.

Filed Jan. 16, 1959, Ser. No. 787,272

3 Claims. (Cl. 144—309)

The invention relates to lumber which is upgraded by removing the defects therein and again making the product whole; and, more particularly, to a method of reconstituting lumber by which the product has characteristics of a homogeneous nature.

Under conventional timber growing conditions and subsequent sawmill practice, only a small fraction of the lumber produced is of the higher grades. For example, in the Western Pine industry, the industrial average of "B and Better" lumber grade, the highest recognized lumber grade, constitutes only approximately three-quarters of 1% of the total lumber produced.

Since over 99% of the lumber manufactured is of poorer quality, a wide range of price exists between the various grades. Competition forces the price of many of the lower grades below cost and, as a consequence, it is common practice to price the higher quality lumber sufficiently high so as to "pull the lower grades through the mill." It is therefore highly advantageous, not only for the producer but for the consuming public as well, if lumber of the poorer grades can be upgraded, or "beneficiated," as it were, to borrow a term from the mining and ore-treatment art.

Advances have been made in the past in this direction, and such items as flooring, drawer fronts, desk tops and laminated beams have been produced, using lower and less-wanted grades, and upgrading the lumber by ripping, trimming and gluing.

So far as is known, however, the heretofore employed methods, and the products thereof, have involved no conscious predetermination and selection having as a very important end result a reconstituted piece of lumber having homogeneous characteristics.

In short, the prior efforts in upgrading lumber have failed to recognize the importance of producing not only a clear grade of lumber but one which has, as well, a substantial uniformity with respect to such properties as grain, color, texture, cell structure and moisture content.

It is therefore an object of the invention to provide a method of reconstituting lumber in which the end product whose properties are very similar throughout.

It is another object of the invention to provide a method wherein the end result is a reconstituted piece of lumber comparable in substantially all respects to the original except for the removal of the defects in the original.

It is yet another object of the invention to provide a method of constituting lumber in which the end product is of a considerably higher grade than the original.

It is another object of the invention to provide a generally improved method of reconstituting lumber and product thereof.

Other objects, together with the foregoing, are attained in the procedures and products described in the following description and shown in the accompanying drawing, in which:

Figure 1 is a perspective of a simplified form of a typical piece of lumber having a number of defects, showing

2

in outline the cuts to be made as steps in the method of the invention;

Figure 2 illustrates a typical relationship of the board components after removal of the defects;

Figure 3 is a fragmentary perspective of a flat grained piece of lumber, showing in outline the cuts to be made as a step in the process of the invention; and

Figure 4 is a view comparable to that of Figure 3 but with the components reassembled to form a vertically grained piece of homogeneous characteristics.

While the method of the invention is susceptible of variations depending upon the environment and upon the requirements of the end product, substantial numbers of the herein shown and described embodiments have been produced by the methods described herein with eminently successful results.

With reference to Figure 1, a piece of lumber 6, or board, is shown as having a typical grouping of defects, such as knots 7, 8 and 9. As frequently occurs, certain of the knots, in this instance knot 7 and knot 8, are disposed in rough alignment on the same side of an imaginary longitudinal plane designated by the numeral 11, the numeral 11 also designating the longitudinal saw cut or rip cut to be made. The knot 9, on the other hand, is on the opposite side of the plane 11.

Either by eye or by measurement, a sawyer having experience in this procedure can quickly ascertain the number and location of the longitudinal planes or cuts which should be applied in order to give maximum yield.

In very simple situations, such as that shown in Figure 1, a single longitudinal cut 11 will suffice. In other cases, two or even more cuts are often required to effect optimum results.

In any event, the step of longitudinal cutting, or ripping, produces two or more elongated strips, such as the strips 13 and 14 in Figure 1.

A plurality of pairs of transverse cuts, such as are indicated by the reference numerals 17, 18 and 19 in Figure 1, is then made, the cuts straddling the defects to permit their removal.

As a consequence of this step, the strip 13 is divided into three portions, 21, 22 and 23, whereas the strip 14 is divided into the two portions 26 and 27.

Special attention is invited, at this juncture, to the fact that the reassembling of the portions 21-27, as appears in Figure 2, is very carefully effected so that the portions 21-27, which are the remaining components of the original board, assume substantially the same physical relationship or juxtaposition that they did in the original board.

Thus, when the portion 21 is end joined to the portion 22 along the joint 31, and the portion 22 is glued to the portion 23 along the joint 32, the resultant strip 36 is very near in physical shape and size to the original strip 13; and the various characteristics of the components 21-23, such as color, grain, texture, etc., are substantially identical to those of the original strip 13. In addition, the color, grain, texture and moisture content of each of the portions 21-23 is substantially the same and the 60 reconstituted strip 36 is therefore uniform in appearance, in working properties, etc. throughout its entire length.

Comparable remarks apply to the reconstituted strip 37 formed by end joining the portions 26 and 27 along the joint 38.

65 In other words, whereas previously used methods employed random pieces, each of different properties, and produced reconstituted lumber of markedly varying properties, the instant process yields an extraordinarily homogeneous product of very high grade throughout.

70 The same procedure is utilized with respect to reconstituting the entire board, the strips 36 and 37 being edge joined along the joint 39 in such a way that the recon-

stituted board 41 closely resembles the original board 6, is homogeneous in all aspects and the constituents or components in the final product each bear substantially the same spatial relation to the others as they did in the original board.

The grain pattern in Figure 1 has been carried through to Figure 2 to illustrate this relationship and shows the homogeneous nature of the product. Obviously, color, texture and moisture content, to name but some of the important properties, will be of a comparably homogeneous nature throughout, quite unlike the random situation which prevails under previously suggested procedures.

Perhaps homogeneity is of greatest importance where the wood is to be left unpainted in use and is, for example, to be treated only with a light stain, as in the case of a molding. In this situation, the reconstituted strips 36 and 37 are cut to the same width and end jointed to form one long, continuous strip (not shown). Being from the same original piece, such a strip would be of very nearly the same color and texture throughout, a feature of great esthetic and commercial importance.

Wood for use in making foundry patterns must also be homogeneous, particularly with respect to its "working" properties governed by such factors as texture, grain, structure and moisture content.

As is shown most clearly in Figures 3 and 4, a piece of lumber 51 having a slash or flat grain structure is ripped longitudinally to form a suitable number of individual strips; for example, the board is cut as at 52 and 53 and yields individual strips 56, 57 and 58, each of which is characterized by a flat, horizontal grain, as appears in Figure 3.

It is common industry practice, particularly in the Western Pine region, to convert substantially all of the log into slash grain lumber. For carving, forming wood-working and pattern-making purposes, however, vertical grain is preferable. In order to achieve a vertical grain structure, the method of the invention provides for rotating each of the pieces 56-58 through ninety degrees and reconstituting them into a board 61, as by gluing the adjacent faces along the joints 62 and 63, the board 61 thereby having a substantially uniform vertical grain structure, as appears in Figure 4. As in the previous description, the resultant product, the board 61, is uniform throughout in respect to its various properties.

While Figures 3 and 4, and the foregoing description relative thereto, refer specifically to lumber without defects, it is to be understood that in the event the original board 51 contains defects, such defects would be removed in the manner previously described and shown in Figures 1 and 2.

It is also to be noted that in some instances a piece of lumber contains, by chance, defects which are, in the main, in transverse alignment rather than in the longitudinal alignment, as appears in the strip 13 shown in Figure 1. In this event, a pair of transverse cuts straddling the transversely aligned defects would be made, the cuts extending entirely across the piece. After removal

of the cutout containing the defects, the adjacent ends of the clear, remaining pieces would be butt joined. In still other cases, only a portion of the defects, only the worst ones, for example, would be removed.

In other words, upgrading or beneficiation in a variety of manners is possible, combinations of longitudinal ripping, as by gang saws, and transverse or cross cuts being utilized in order to produce the optimum yield for the particular piece being treated.

Regardless of the combination employed, however, the end product is one which is characterized by a homogeneity heretofore unobtained by any known methods. The components in the reconstituted lumber are in a juxtaposition markedly similar to that which obtained in the original piece, a superior product is yielded, an economic loss is converted to a gain and the interests of conservation are served.

What is claimed is:

1. A method of reconstituting lumber comprising the steps of ripping longitudinally an elongated board containing a plurality of defects into a plurality of strips at least some of which strips contain at least one defect, of cutting out each of said defects in said strips by transversely severing said strips on opposite sides of the defects therein, removing said severed portions containing said defects, of end gluing each remaining portion of each of said strips to form a plurality of reconstituted clear strips, and of gluing said strips to each other to form a reconstituted clear board, each of said strips being glued to a strip which was originally thereadjacent whereby said glued product is of substantially uniform homogeneity.

2. The method of claim 1 wherein each of said strips is end joined to its originally adjacent strip.

3. A method of reconstituting a board having defects into a clear board having substantially identical characteristics as the original, said method comprising the steps of cutting said original board into a plurality of strips, of cutting each of the defects out of each of the strips containing defects by transversely severing said strips on opposite sides of the defects therein, removing said severed portions containing said defects, of end joining each of the remaining portions of each of the strips, and of edge joining each of said strips to the others, each of said strips being glued to a strip which was originally thereadjacent whereby said glued product is of substantially uniform homogeneity.
